UNITED STATES PATENT OFFICE

CHARLES P. BEARDSLEY, OF REINBECK, IOWA.

POWER-DRIVEN HAIR-CLIPPER.

1,133,980.

Specification of Letters Patent.

Patented Jan. 3, 1915.

Application filed March 17, 1914. Serial No. 825,268.

To all whom it may concern:

Be it known that I, CHARLES P. BEARDSLEY, a citizen of the United States, residing at Reinbeck, in the county of Grundy and State of Iowa, have invented certain new and useful Improvements in Power-Driven Hair-Clippers, of which the following is a specification.

The present invention relates to certain new and useful improvements in power driven hair clippers, and has for its object to provide a device of this character which embodies novel features of construction whereby the power received from a flexible shaft can be effectively applied to the blades to operate the same.

A further object of the invention is to provide a hair clipper of this character which is light in weight and can be easily handled and manipulated, which is simple and inexpensive in its construction, and which can be easily assembled or taken apart as may be desired.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a top plan view of a power driven hair clipper constructed in accordance with the invention. Fig. 2 is an enlarged longitudinal sectional view through the same. Fig. 3 is a transverse vertical sectional view on the line 3-3 of Fig. 2. Fig. 4 is an enlarged plan view of the blades, the reciprocating blade being superposed upon the fixed blade in operative position. Fig. 5 is an end view of the two blades, and Fig. 6 is a view similar to Fig. 2, showing a modified construction of the cam mechanism.

Corresponding and like parts are referred to in the following description and indicated in all the views of the drawing by the same reference characters.

Specifically describing the present embodiment of the invention, the numeral 1 designates the stock of the tool which is provided with a suitable handle 2, the said handle being shown in the present instance as integral with the stock and projecting longitudinally from one end thereof. One

side of the stock 1 is recessed at 3 and provided with a chamber 4 opening through the said recess.

A fixed blade 5 extends across the mouth 60 of the recess 3, the heel of the said blade being provided with positioning lugs 6 which fit in corresponding sockets 6^a in one side of the stock, while the teeth 5^a of the blade project outwardly from the opposite 6^b side of the stock.

Slidably mounted upon the fixed blade 5 is a reciprocating blade 7, the teeth 7^a thereof being adapted to coöperate with the teeth 5^a of the fixed blade 5 to cut hair or the like 7^b when the reciprocating blade is moved back and forth.

A pair of tension screws 8 project upwardly from the fixed blade 5 and are received loosely within slots 9 formed in the reciprocating blade so as to coöperate therewith to direct the reciprocating blade in its back and forth movements. The said tension screws 8 extend upwardly through the stock 1 and are capped by thumb nuts 8^a, so spring washers 8^b being interposed between the nuts and the upper ends of the blades. It will thus be obvious that the tension between the blades can be regulated as desired by tightening or loosening the thumb nuts 8^a. It will also be observed that a series of anti-friction rollers 10 are interposed between the heel portions of the two blades so as to eliminate as much friction as possible. These anti-friction rollers may be mounted in any suitable manner, although in the present instance they are shown as received within corresponding guide grooves 11 formed in the opposed faces of the blade.

A drive shaft 12 extends through the handle 2 and stock 1 and projects into the chamber 4 of the latter. Arranged within the chamber 4 and fitted upon the projecting end of the shaft 12 so as to rotate therewith is a cylinder 13. In the present instance this cylinder is shown as having a feather and spline connection 14 with the shaft 12 so that the parts can be readily dismounted by withdrawing the shaft 12 longitudinally from the chamber 4 and thereby disengaging it from the cylinder 13.

An annular cam rib 15 surrounds the cylinder 13 and is received between a pair of spaced pins 16 projecting upwardly from the reciprocating blade 7, said pins being preferably provided with anti-friction rollers 17. With this construction it will be

obvious that as the cylinder 13 is rotated the cam rib 15 thereon will coöperate with the rollers 17 of the pins 16 to impart a back and forth reciprocating movement to the 5 blade 7.

Thrust bearings are preferably provided at each end of the cylinder 13. These may be of any suitable construction, although in the present instance one bearing plate 18 10 is shown as surrounding the shaft 12 and fitted into one end of the chamber 4, while a second bearing plate 19 is fitted upon the end of the shaft 12 and engaged by a spring washer 20.

15 The two plates 18 and 19, as well as the ends of the cylinder 13, are provided with annular raceways receiving the anti-friction balls 21 which are interposed between the said plates and the cylinder.

20 An adjusting screw 22 which is threaded in the end of the stock 1 engages the spring washer 20 and provides a means for tightening and loosening the thrust bearings as found necessary. It will also be obvious 25 that by sufficiently loosening this screw the bearing plate 19 can be removed preparatory to dismounting the mechanism.

A modification is illustrated by Fig. 6, in which the cam mechanism is so constructed 30 as to prevent breakage should a pin or other obstruction be encountered by the blades. The two blades themselves are constructed and mounted as in the previous instance, although the annular cam rib 15^a, instead of 35 being integral with or rigidly mounted upon the cylinder, is carried by a ring 24 which is mounted upon the cylinder 13^a to slide longitudinally thereon, but has a feather and spine connection therewith. Collars 25 40 are threaded or otherwise removably fitted upon opposite ends of the cylinder 13^a and springs 26 are interposed between the said collars and the ring 24 so as to hold the same yieldingly in operative position. These 45 springs 26 are sufficiently strong to hold the ring 24 in position and cause the cam rib 15^a to operate the reciprocating blade 7 under ordinary conditions, although should a pin or other obstruction be encountered by 50 the cutting teeth of the blades so as to clog the same, the springs 26 would permit the ring 24 to slide back and forth on the cylinder 13^a as the latter revolved with the shaft 12, thereby preventing any shock or injury 55 and enabling the shaft 12 to rotate without operating the blade 7. In this modified construction it will also be observed that the anti-friction rollers 21 are interposed between the bearing plates 18 and 19 and the 60 respective collars 25, the latter having suitable raceways formed therein.

In both forms of the invention the outer end of the drive shaft 12 is designed to be connected to a flexible shaft 28 which may receive power from a fixed motor. The tool 65

is light in weight and compact in construction so that it can be easily guided and manipulated when held by the handle 2 and the rotation of the shaft 12 operates through the cam mechanism, as has been previously 70 described to reciprocate the blade 7 of the cutting mechanism.

Having thus described the invention, what I claim as new and desire to secure by Letters Patent, is:—

75 1. A power driven hair clipper including a stock, a fixed blade applied to the stock, a reciprocating blade mounted upon the fixed blade, a pair of pins projecting from the reciprocating blade, a shaft journaled upon the stock, a cylinder fixed upon the shaft, thrust bearings for the cylinder, and an annular cam rib carried by the cylinder and received between the before mentioned pins for coöperation therewith to actuate the 80 reciprocating blade.

2. A power driven hair clipper including a stock, a fixed blade applied to the stock, a reciprocating blade mounted upon the fixed blade, a pair of pins projecting from the reciprocating blade, a shaft journaled upon the stock, a cylinder fixed upon said shaft, thrust bearings for the cylinder, means for adjusting the thrust bearings, and an annular cam rib carried by the cylinder 95 and received between the before mentioned pins for coöperation therewith to actuate the reciprocating blade.

3. A power driven hair clipper including a stock, a fixed blade applied thereto, a reciprocating blade mounted upon the fixed blade, roller bearings between said reciprocating blade and fixed blade, a pair of pins projecting from the reciprocating blade, a shaft journaled upon the stock, a cylinder 100 fixed upon the shaft, and an annular cam rib carried by the cylinder and received between the before mentioned pins for coöperation therewith to actuate the reciprocating blade.

4. A power driven hair clipper including a stock, a fixed blade applied thereto, a reciprocating blade mounted upon the fixed blade, a shaft journaled upon the stock, and cam means yieldingly mounted upon said 115 shaft and adapted to actuate the reciprocating blade.

5. A power driven hair clipper including a stock, a fixed blade applied thereto, a reciprocating blade mounted upon the fixed blade, a pair of pins projecting from the reciprocating blade, a shaft journaled upon the stock, a cylinder slideable back and forth upon the shaft but rotatable therewith, an annular cam rib carried by the cylinder and 125 received between the before mentioned pins of the reciprocating blade to operate the latter, and yielding means normally holding the cylinder against sliding movement.

6. A power driven hair clipper including 130

1 stock, a fixed blade applied thereto, a reciprocating blade mounted upon the fixed blade, a pair of pins projecting from the reciprocating blade, a shaft journaled upon the stock, a cylinder fixed upon said shaft, a ring slidable back and forth upon the cylinder but rotatable therewith, an annular collar carried by the ring and received between the before mentioned pins of the reciprocating blade to operate the latter,

collars fitted upon opposite ends of the cylinder, and springs interposed between the collars and the ring to normally prevent sliding movement of the ring.

In testimony whereof I affix my signature in presence of two witnesses.
